UNITED STATES PATENT OFFICE.

GEORGE H. A. KOHLER, OF NEW YORK, N. Y., ASSIGNOR TO TUCKAWAY FOLDING LADDER COMPANY, INC., A CORPORATION OF NEW YORK.

COLLAPSIBLE STEP-LADDER.

1,267,670.

Specification of Letters Patent. Patented May 28, 1918.

Application filed July 10, 1917. Serial No. 179,618.

To all whom it may concern:

Be it known that I, GEORGE H. A. KOHLER, a citizen of the United States, and a resident of the borough of Bronx, city, county, and State of New York, have invented certain new and useful Improvements in Collapsible Step-Ladders, of which the following is a specification.

This invention relates to improvements in ladders and has for its object the production of a collapsible step-ladder which can be folded into an extremely small compass and which possesses unusual strength and rigidity when in an operative position, but is neither complicated nor expensive to manufacture.

The invention is fully set forth and described in detail in the following specification and drawings forming a part thereof in which;

Figure 1 is a front elevation, partially broken away, showing the ladder closed;

Fig. 2 is an end elevation showing the ladder closed;

Fig. 3 is a similar view showing the ladder opened;

Fig. 4 is a fragmentary top plan view of a single step;

Fig. 5 is a bottom plan view of the same;

Fig. 6 is a rear elevation of the rear legs, closed;

Fig. 7 is a fragmentary end elevation, of the ladder when opened, showing means for locking the spreader;

Fig. 8 is a front perspective view of upper portion of ladder when open;

Fig. 9 is a similar view of lower portion of the ladder;

Fig. 10 is a fragmentary rear elevation corresponding to Fig. 6 with the ladder open, showing position of the cross braces.

Referring to the drawings and the construction shown therein the reference numeral 1 designates the uprights of the main

ladder structure and 2 the rear legs of the ladder. The said uprights are secured by means of connecting straps or plates 3, which are provided with inturned ends 4,

50 to cross pieces 5. Preferably said plates which envelop said cross pieces are secured thereto by means of pins 6, which extend completely through said cross pieces and are riveted at each of their ends. As shown said straps 3 project upwardly from the top

of said uprights a sufficient distance to serve 5 as an efficient support for the cross pieces 5 which fit therebetween. Normally said cross pieces when the ladder is in the collapsed position shown in Fig. 1, rest on the tops of said uprights but when the ladder is in 60 the open position as shown in Fig. 3, the outer transverse top edges *a* only of said uprights bear against said cross pieces 5. The rear legs are also provided at their top ends with angular straps 7 having inturned 65 ends adapted to embrace said legs similar to the ends 4, above described. These straps are secured by means of pins 8 and 9, the ends of which are riveted to the upper ends of said legs and to the upper ends of the 70 rear uprights, said straps being adapted to receive between them the cross pieces 5 through which the pins 9 extend.

The uprights 1 are provided with steps which are formed of two hinged leaves 10 75 and 10' respectively, and these leaves are pivotally mounted by means of straps 11 on U-shaped rods 12, the ends of which rods are anchored in the uprights 1 at points where the same are reinforced by means of 80 bands 13. Preferably as shown the inturned ends of the rods 12 extend through the said uprights substantially to one side of the center as shown in Fig. 7, whereby the substantial weakening of such uprights is 85 avoided. A pair of slideable braces 14 are pivotally secured to each of said leaves, one of said braces encircling a front and the other a rear upright at their respective lower ends. Stop pins 15 are provided at the inner faces of the uprights 1 so as to limit the downward movement of the lower ends of the braces and as shown said pins are so positioned that the central portion of each of the steps will be rigidly supported by 90 said braces 14 in a horizontal position when the ladder is in the open position shown in Fig. 3.

The cross pieces 5 are adapted to rest on the upper ends of the rear legs 2 when the 100 ladder is in the open position shown in Fig. 3 and in such position the cross pieces 5 are horizontal. Accordingly the spreading of the rear legs into the position shown in Fig. 3 results in maintaining the front and 105 rear uprights in parallel relation, and as a consequence the steps will not only be horizontal in the position shown in Fig. 2

when the rear legs are in a folded position but also when the rear legs are spread as above stated.

Spreaders 16 are pivotally secured at one end by means of pins 17 to the rear uprights of the ladder and at their opposite ends they are pivotally secured to loose fitting collars 18 which are slidably mounted on the rear legs of the ladder. A spring catch 19 serves to hold the spreaders in a substantially horizontal position when the ladder is in the open position shown in Fig. 7, but on manually depressing said catch the collar 18 may be moved into the position shown in Fig. 2 whereby said legs are snugly folded against the rear uprights of the ladder. Cross-braces 20 are pivotally secured to said collars 18 at one end and at their opposite end to collars 21, the latter being limited in their downward movement by means of stop pins 22, so that when the ladder is in the position shown in Fig. 7 said cross-braces will be in the position shown in Fig. 10.

When it is desired to fold up the ladder the catch 19 is depressed, as above stated, the rear legs are folded in the position shown in Fig. 2 the collar 18 assuming the position therein shown. In this position the leaves 10, 10', will still be horizontal. The ladder is now folded in a direction at right angles to the aforesaid folding movement and the leaves of the steps will then assume the positions shown in Figs. 1 and 2, while the two front uprights will be in close proximity to each other as shown in Fig. 1.

The foregoing ladder may be constructed of white wood, oak, or other suitable wood, or of metal, or of any other desired material, but preferably I construct the uprights and rear legs of oak and provide metal straps and reinforcing bands as previously stated. Such a construction is sufficiently strong for all ordinary purposes, while at the same time it is extremely economical to manufacture.

This ladder is particularly adapted for use in apartments and under similar conditions where economy of space is important, but it is so strong that it can be used in all cases as a substitute for a non-collapsible step-ladder.

Having thus described my invention, what I claim and desire to secure by Letters Patent is:

1. In a collapsible step-ladder, the combination comprising two pairs of lateral up-

rights, a plurality of folding steps having a central hinge and pivotally supported between the uprights, horizontal cross-bars 60 pivotally connected to the front and rear uprights of each pair adjacent the top-ends thereof, a pair of rear legs for supporting the ladder in a self-supporting position, said rear legs being pivotally secured to 65 said cross-bars and to said rear uprights of each lateral pair at spaced points, so as to provide a lever arm between said points, two pairs of slideable braces the upper ends of each pair being pivotally secured to said 70 steps adjacent the center thereof and the lower ends being slidably secured to the respective pairs of lateral uprights, and stops for limiting the downward movement of said braces.

2. In a collapsible step-ladder, the combination comprising two pairs of lateral uprights, a plurality of cross-rods each having inturned ends which project at substantially right angles to their axes and forming integral pintles which extend through and pivotally engage the respective members of each pair of uprights substantially to one side of the center of each upright, a plurality of centrally-hinged folding steps, each 80 step being of greater width than a single upright and being pivotally secured at its respective outer ends to opposing cross-rods connecting the respective members of each pair of uprights.

3. In a collapsible step-ladder, the combination comprising two pairs of lateral uprights a corresponding series of reinforcing metal bands substantially enveloping and being spaced at intervals along each upright 95 of each pair, a plurality of cross rods each having inturned ends which respectively project completely through a different member of each pair of said bands and extend to one side of the center of the upright carrying said band, said inturned ends of such cross rods forming integral pintles adapted to pivot in the upright engaged thereby, a plurality of centrally-hinged folding steps, each step being of greater width than a single upright and being pivotally secured at its respective outer ends to opposing cross-rods connecting the respective members of each pair of uprights.

Signed at New York, in the county of New York and State of New York, this 9th day of July, 1917.

GEORGE H. A. KOHLER.
